UNITED STATES PATENT OFFICE.

LUNA H. THRALLS, OF HYMERA, INDIANA.

DESIGN FOR A WASHTUB.

56,638.

Specification for Design.

Patented Nov. 16, 1920.

Application filed April 16, 1920. Serial No. 374,479. Term of patent 7 years.

To all whom it may concern:

Be it known that I, LUNA H. THRALLS, a citizen of the United States, residing in the town of Hymera, county of Sullivan, and State of Indiana, have invented a new, original, and ornamental Design for a Washtub, of which the following is a specification, reference being had to the accompanying drawing, forming part thereof.

The figure is a perspective view of the washtub, showing my new design.

I claim:—

The ornamental design for a washtub, as shown.

LUNA H. THRALLS.
